UNITED STATES PATENT OFFICE.

ISAAC G. TREAT, OF READING, PENNSYLVANIA.

ICE-CREEPER.

SPECIFICATION forming part of Letters Patent No. 286,240, dated October 9, 1883.

Application filed July 31, 1883. (No model.)

To all whom it may concern:

Be it known that I, ISAAC G. TREAT, a citizen of the United States, a resident of the city of Reading, county of Berks, and State of Pennsylvania, have invented a new and useful Improvement in Ice-Creepers, of which the following is a specification.

This improvement relates more particularly to that class of ice-creepers which are 10 permanently attached to the boot or shoe.

The object of the improvement is to furnish an ice-creeper free from the objections usually made to the same of non-retention of place when used as a creeper, and of wear of sole 15 when not in use for that purpose. This I attain by the construction shown in the accompanying drawings, forming part of this specification, and in which like letters designate like parts.

Figure 1 represents the improvement attached to the inner face of the heel, with the spur-arm raised clear of both heel and sole. Fig. 2 shows the spur-arm turned back upon the heel, with the spurs protruding from the 25 same to catch upon the ice. Fig. 3 represents the arm reversed upon the sole and supported upon the sole-plate guard. Fig. 4 is a front and vertical plan of the creeper heel-plate, and of the arm-spring. Fig. 5 is a 30 plan, side, and end elevation of the spur-arm, showing spurs, journals, and finger-recess for same.

A represents the boot or shoe; A', the heel; B, the heel-plate; B', raised ends; B², screw-holes; B³, journal-lugs; C, a flat steel spring; D, spur-arm; D', spur-head; D², journal-head; D³, journals; D⁴, ice-spurs; D⁵, finger-recess; E, sole-guard; E', guards; E², screw-holes.

40 The construction of the improvement is as follows: The heel-plate is so constructed that it is molded complete, requiring no machine-work. The spring C is a plain flat piece of spring-steel cut to lie between the raised ends 45 B', and is supported on a portion of the plate B, left standing at each end inside of the raised portion B', the plate being cut out sufficiently longitudinally to permit the depression of the spring C in vibrating the arm

D. The spur-arm D is cast complete with 50 its spurs and journals, of the form shown, and the back of the journal-head has three teats formed upon it, which, in combination with the spring C, retain the arm D in the three positions shown in Figs. 1, 2, and 3. 55 The sole-guard E is also a single piece of casting, with the height of the guards E arranged to receive the spur-head and prevent the penetration of the sole by the spurs D⁴.

It will be apparent from the above description that the improved ice-creepers are inexpensive in construction in their several parts.

To assemble the plate B, spring C, and arm D, for application, the heel-plate B, which is of cast malleable iron, is slightly bent outward at the center, which opens a wider space between the journal-lugs B³, and permits the insertion of the journal-head and journals of the spur-arm. The spring C is 60 first slipped through the journal-lugs B³. The journal-head is then placed between the same, and the plate B is straightened, which, again closing the space between the extreme ends of the lugs B³, locks the journals D² 65 within the same and retains the spur-arm in place. A finger-recess, D⁵, is formed in the face of the spur-head, whereby the same may be raised from its working position upon the heel, as in Fig. 2, and may be placed in a non-working position on the sole-guard, as shown 70 in Fig. 3. The plate and guard are attached to the heel and sole, as shown, by ordinary 75 gimlet-screws.

Having shown the construction and application of my improved ice-creeper, I desire to secure by Letters Patent the following claims thereon:

1. In an ice-creeper, the combination, with a skeleton plate adapted to be attached to the heel of a boot or shoe, of a spur-arm, D, having journals D², integral therewith, a finger-recess, D⁵, the usual ice-spurs, D⁴, a plain flat spring, C, retained in place by lugs B³ and offsets B', with a sole guard-plate, E, having 90 guards E', secured to the sole of the boot or shoe, substantially as shown, and for the purpose described.

2. In an ice-creeper, as described and in combination therewith, a sole-guard plate, E, provided with projected guards E', adapted to be secured to the sole of the boot or shoe, 5 and to receive upon said guards the reversed spur-head of the spur-arm D when turned from the heel to a non-acting position under

the instep, whereby the ice-spurs D' are prevented from puncturing the sole, substantially as and for the purpose set forth.

ISAAC G. TREAT.

Witnesses:

THOMAS P. KINSEY,
F. PIERCE HUMMEL.
